VENDING MACHINE CABINET

Iber C. Courson, Longmeadow, Mass., assignor to
Westinghouse Electric Corporation, a Pennsylvania
corporation

Filed Apr. 28, 1965, Ser. No. 84,988

Term of patent 14 years

(Cl. D52—3)

The figure is a perspective view of a vending machine cabinet embodying my new design. The side not shown is a mirror image of the side shown and the top and rear of the cabinet are plain and unornamented.

The dominant features of my design reside in the portions shown in full lines.

I claim:

The ornamental design for a vending machine cabinet, substantially as shown and described.
